UNITED STATES PATENT OFFICE.

JOHN WIGHTMAN, OF NOTTINGHAM, ENGLAND.

DESIGN FOR A COLLAR OR RUFFLE.

SPECIFICATION forming part of Design No. 20,569, dated March 10, 1891.

Application filed January 30, 1891. Serial No. 379,725. Term of patent 3½ years. Patented in England September 22, 1890, No. 157,214.

To all whom it may concern:

Be it known that I, JOHN WIGHTMAN, a subject of the Queen of Great Britain, residing at Nottingham, England, have invented and 5 produced a new and original Design for a Collar or Ruffle, (which has been patented by me in Great Britain, No. 157,214, dated September 22, 1890,) of which the following is a specification, reference being had to the accompanying drawing, forming part thereof, which represents a side elevation and a cross-section of a collar embodying my design.

The design embraces two characteristic features: first, a series of spire-like figures A of 15 graduated height, whereby the upper edges appear to taper from the center downward in direction of the ends, and the second feature is a series of ruffle-like figures B, arranged upon the outer side of and concealing the base of the spire-like figures. The spire-like 20 figures have the appearance of being closely stepped, their tops being ornamented and their body portion plain. The ruffle-like figures are arranged in triangular groups and have a rosette appearance. 25

I claim—

A design for a ruffling, substantially as shown and described.

JNO. WIGHTMAN.
